(57) **CLAIM**

The ornamental design for a water compatible or dry use female athletic garment having neoprene prosthetic attachments, as shown and described.

DESCRIPTION

FIG. 1 is a front perspective view of a neoprene prosthetic.

FIG. 2 is a front elevational view of the neoprene prosthetic.

FIG. 3 is a rear elevational view of the neoprene prosthetic.

FIG. 4 is a top plane view of the neoprene prosthetic.

FIG. 5 is a bottom plane view of the neoprene prosthetic.

FIG. 6 is a left side elevational view of the neoprene prosthetic.

FIG. 7 is a right side elevational view of the neoprene prosthetic.

FIG. 8 is a front perspective view of one neoprene prosthetic configured to the right side of a female athletic garment.

FIG. 9 is a front perspective view of one neoprene prosthetic configured to the left side of a female athletic garment; and,

FIG. 10 is a front perspective view of one neoprene prosthetic configured to the right side of the female athletic garment.

Any shadings and cross hatchings are not features of the design but are utilized to illustrate the contours of the present disclosure.
